UNITED STATES PATENT OFFICE.

ERNEST E. SABIN, OF BEVERLY, AND ERIC A. HOLMGREN, OF LYNN, MASSACHUSETTS,
ASSIGNORS TO UNITED SHOE MACHINERY CORPORATION, OF PATERSON, NEW
JERSEY, A CORPORATION OF NEW JERSEY.

INSOLE-MAKING MACHINE.

Application filed June 4, 1927. Serial No. 196,580.

This invention relates to machines for making such composite articles as the insoles for shoes disclosed in Letters Patent of the United States No. 1,382,818, Bunkers & Bradford, June 28, 1921. In these insoles there are combined a sheet of body-material, which may be leather or a leather-substitute, and a sheet of canvas or other fabric, in which a sewing rib is molded. In manufacturing such insoles, it is necessary to first form the rib in the fabric, and then assemble the ribbed sheet and the body-sheet, securing them to each other. The present invention has among its objects the provision of a machine which while relatively inexpensive, especially as to the outlay necessary for the forming dies, and occupying but small space, will produce such insoles rapidly and efficiently.

In the attainment of these objects, there are combined, in the illustrated machine, a carrier having a plurality of work-supporting sections and movable to different operating positions, and a plurality of operating mechanisms, one of which is arranged to act upon plural carrier-sections, while the other mechanisms act upon particular sections only. By making the mechanism common to plural carrier-sections that which effects the forming of the material, as the molding of the sewing rib and the pressing together of the layers, the cost of the apparatus may be reduced, since there are required fewer dies, which dies are in comparatively large sets corresponding to different sizes of insoles. Feeding mechanisms, which may supply, respectively, the body-material of an insole and the fabric layer, act only upon particular sections of the carrier. The preferred organization involves a carrier, shown as a reciprocating plate having two sections, which may be presented simultaneously at two of three successive positions, the outer positions having mechanisms which supply the two kinds of work-pieces to respective carrier-sections, while the mechanism at the intermediate position applies pressure to the delivered pieces. The movable carrier-portion of such an organization may be light, with small inertia, and consequently may be operated rapidly, with the expenditure of little power. Registration between the carrier-elements and those at the operating positions may be readily effected and with accuracy at the two extremes of travel. The operating mechanisms may be in pairs at opposite sides of the carrier, the rib-molding projection with which a section of the carrier is provided extending between the opposite faces and serving for both. In this way, two insoles, a right and a left, may be produced at the same time with an economy in the production of the dies. Moreover, the pressure applied to the carrier by the mechanisms in duplicate is balanced. Each section is best so mounted that its operating surface or surfaces lie generally in substantially vertical planes, to which the feeding mechanisms deliver, and means is furnished, as at the upper edges of the surfaces, for holding the supplied pieces. This holding or retaining means is shown, in one instance, as furnished by suction devices, and in another by spurs, the former well lending itself to the retention of the fabric, while the latter is effective in connection with the leather or other body-material. With the mechanism at one of the positions, as that which feeds the body-material and to which is brought a completed insole, may be associated a delivering mechanism, which removes the work from the carrier. When two insoles are formed at opposite sides of the carrier, this mechanism grasps and delivers these simultaneously. In the present embodiment of the invention, the pressure mechanism, which is identified with a particular position includes a die, grooved and complementary to the rib-forming projection upon the die-section of the carrier, which die has means, as, for example, its groove, for retaining upon it the formed insole-piece during the travel of the associated die. To free the work from this retaining means, there is provided some such means as air under pressure.

To deliver the insole-pieces to a substantially vertical operating face of the carrier or other support, there is present, as another feature of the invention, means arranged to receive the pieces in a substantially horizontal position, and elevate and apply them to the operating face. To the elevating member in its horizontal position, the pieces may be transferred from a magazine, while at the operating face, it presses said pieces against the retaining device with which the carrier is provided. When the carrier is

double, with two operating faces at opposite sides of a reciprocatory plate, as already pointed out, the elevating means is correspondingly duplicated, receiving the pieces 5 through transferring mechanisms from a magazine situated at each side of the path of the carrier.

In the accompanying drawings illustrating the invention in one of its many possible 10 forms,

Fig. 1 is a top plan view of the machine, with the upper portion of the frame broken away and parts in section;

Fig. 2 is an enlarged vertical sectional 15 detail of one of the air-controlling valves on the line II—II of Fig. 1;

Fig. 3 is a broken side elevation of the entire group of these valves;

Fig. 4 is an irregular longitudinal section 20 taken along a plane in front of the main cam-shaft;

Fig. 5 is a detail in broken side elevation of the delivering device for the finished work;

Fig. 6 is an irregular vertical transverse section taken at the left of the leather-feeding mechanisms in Fig. 4;

Fig. 7 is a horizontal section on the line VII—VII of Fig. 6;

Fig. 8 is a vertical sectional detail of the actuating means for the pressure-applying mechanism;

Fig. 9 is a vertical sectional detail on the line IX—IX of Fig. 4;

Fig. 10 is a full vertical sectional detail of a portion of the pressure-applying mechanism in co-operation with the carrier mechanism and taken on the line X—X of Fig. 11, with parts broken away;

Fig. 11 is a full horizontal section on the line XI—XI of Fig. 10;

Fig. 12 is a full vertical transverse section on the line XII—XII of Fig. 10;

Fig. 13 is a vertical transverse section on the line XIII—XIII of Fig. 1;

Fig. 14 shows the fabric-feeding apparatus in sectional elevation, looking from the right in Fig. 13;

Fig. 15 is a section in a plane parallel to 50 that of Fig. 13, illustrating the fabric-elevating devices;

Figs. 16 and 17 are partial vertical transverse sections on the lines XVI—XVI and XVII—XVII, respectively, of Fig. 1; and

Fig. 18 is an enlarged horizontal, broken, sectional detail on the line XVIII—XVIII of Fig. 4.

Upon a frame F are supported the various elements of the machine, the principal 60 groups of which furnish the carrying mechanism A, by which the work is transferred from one operating position to another and which shares in the insole-forming effects; the feeding mechanism B, by which a layer 65 fabric is supplied to the carrier for the

operation upon it; the leather-feeding mechanism C similarly supplying the carrier; the pressure mechanism D effecting the formation of the work-pieces; and the insole-delivering mechanism E for removing the completed work from the carrier. Since two insoles, a right and a left, are preferably produced simultaneously, the carrying mechanism has opposite receiving and forming surfaces, and the mechanisms B, C and D at the three successive operating positions are correspondingly duplicated.

To describe first the carrying mechanism, there extend transversely of the central portion of the frame two rods 10 spaced one 80 above the other and fixed against movement. Secured at the middle of each rod is a guide member 12, at the adjacent sides of each of which members are ways for a slide 14 movable transversely of the frame. Arranged to reciprocate longitudinally of the frame in ways at the center of the slides 14 is the carrier-slide A. This carrier has two distinct supporting and operating sections 18 and 20 occupying the opposite extremities of the slide. The first of the sections receives upon each of its opposite faces pieces b of some such fabric as canvas of sufficient size to furnish a layer of a composite insole, including a sewing rib a formed in the canvas. This portion of the carrier consists of a metal plate, preferably slotted between its faces to the outline of the insole-rib. In this slot, a metal band 22 (Figs. 10 and 12) is so inserted as to project equally at opposite sides of the plate. Thus there is formed by a single operation a double die, which will produce the sewing rib for both a right and a left insole. Near the upper edge of the section 18 is a horizontal passage 24, from which, back of the canvas piece operated upon, open two nozzles 26, preferably of some such compressible material as rubber. Suction is created at the nozzle 26 through a pipe 28 including a flexible section, to avoid interference with the movement of the slide, and leading to an air-pump 30 driven from a motor 32, which furnishes power for the machine. The flow of air through the nozzles is controlled as will later appear. To the section 20 of the carrier A, pieces c of leather or a leather-like material are supplied, these pieces being of such area that they may be trimmed to furnish, after they have been assembled with the ribbed canvas pieces, completed insoles. The canvas or the leather pieces, preferably the former, may bear upon one face a coating of an adhesive, such as latex, which, while not interfering with their being stacked, will become adhesive under proper conditions of pressure and temperature. This section 20 consists of a plate with parallel plane surfaces having, projecting from their upper portions, retaining spurs 130

34, against which the pieces *c* may be pressed and held for the operation upon them. The spurs preferably have a slight upward inclination, so they resist downward displacement of the pieces which they support, yet permit their free removal in an upward direction. The carrier *A* may be readily removed from its guiding ways and replaced by another bearing a projection 22 adapted to mold the rib in an insole of another size.

To reciprocate the carrier so that the sections 18 and 20 shall alternately occupy positions to co-operate, respectively, with the fabric-feeding mechanism *B* and the pressure mechanism *D*, and then with the pressure mechanism *D* and the leather-feeding mechanism *C*, together with the delivering mechanism *E*, and to give the proper dwell at each position for the various operations to be performed, it is connected to cam mechanism. Joined to the motor 32 by reducing gearing 36 is a main cam-shaft 38 journaled horizontally near the lower portion of the frame and extending longitudinally thereof. This shaft, in addition to its cam-actuating function, operates a group of rotary valves, one of which, designated as 39, governs the suction applied to the vacuum nozzles 26 through the pipe 28, as already indicated. Fast upon the shaft 38 is a double clutch member 40 (Figs. 4 and 18), at the opposite sides of which sleeves 42 and 44 are mounted to rotate about the shaft 38, each sleeve having fixed to it a series of cams. Secured to each sleeve is a clutch member 46, which may carry sliding blocks 48 movable into and out of engagement with lugs upon the corresponding face of the clutch member 40 to produce rotation of the associated sleeve, or to allow it to rest while the companion sleeve is rotated. To actuate the blocks of each member 46, a cam-ring 50 (Fig. 17) is mounted to oscillate beside it about the associated sleeve. A detent 52 movable to engage projections 54 from the periphery of each member 46 stops the latter in a predetermined position. Journaled in the frame, beside the shaft 38, is a shaft 56 (Fig. 18), rotated through reducing gearing 58 from said shaft 38. Fixed to the shaft 56 are two cams 60, 60, one for actuating the rings 50 and the detents 52 of each of the clutch members 46, and arranged to produce rotation of the cam-sleeves 42 and 44 at the correct time in the cycle of the machine. Each of the cams 60 oscillates a bell-crank lever 62 fulcrumed upon a bracket 64 at the rear of the frame. Each lever 62 is joined by a link 66 to the corresponding cam-ring, the connection being continued by a link 68 to a toggle-lever 70, which actuates the detent 52. This clutch and its controlling mechanism are substantially as described in the application filed in the United

States Patent Office April 20, 1922, in the name of Edna A. Perry, executrix of the will of Frederick H. Perry, deceased, this bearing the Serial No. 555,774. A cam 72 upon the sleeve 42 (Figs. 9 and 18) acts 70 upon a lever 74 carrying a roll held against the cam by a spring 76. A link 77 (Fig. 4) is articulated to the lever 74 and to a bell-crank lever 78 linked at 80 to a lever 82 joined by a link 84 to the carrier *A*. 75

The canvas-feeding mechanisms *B*, *B* appear in Figs. 1, 4, 13, 14 and 15. They generally resemble the corresponding mechanism in an application filed in the United States Patent Office April 13, 1925, in the name of Eric A. Holmgren and bearing the Serial No. 22,624. Considering one of these, its companion being identical, mounted upon a bracket 88 projecting from the main frame is a skeleton magazine-frame 90. The vertical elements of the magazine-frame may be supported for adjustment toward and from each other, as is indicated at 92, so they may be varied in position to adapt them to receive pieces of different sizes. Beneath the magazine-frame, and extending axially thereof, is a vertical guide-rod 94 surrounded by a sleeve 96, which carries at its upper extremity a platform 98 for the support of a stack of the canvas pieces *b* to be fed. 95 An arm 100 projects from the bottom of the sleeve, and is guided by a second vertical rod 102. To the arm is connected a cord 104 passing about a stepped sheave 106 and having at its opposite extremity a weight 108, which substantially counterbalances the platform and the supported stack of work-pieces. To raise the platform and stack gradually as the pieces are fed from it one by one, the sheave is rotated in successive steps by engagement with ratchet-teeth 110, which it carries, of a pawl 112 pivoted upon an arm 114 fixed to a shaft 116 extending adjacent to both feeding mechanisms. The shaft 116 has an arm 118 (Fig. 1) joined by a link 110 to a lever 122 fulcrumed below the shaft 38 (Fig. 13). Upon the sleeve 44 (Fig. 18) is a disk 124, in one face of which is a cam-groove 126. A bell-crank lever 128 has at the end of one arm a roll lying within the groove, while the other arm is united by a link 130 to the lever 122. For each oscillation of the lever 122 by the cam, the ratchet mechanism rotates the sheave to raise the platform and thus the top of the stack of work-pieces to a point at least as high as that which was occupied before the removal of the preceding piece. A detent 131 (Fig. 14) contacts with the teeth 110 to retain the platform against downward movement. 125

Through the top of each magazine-frame 90 enters a transferring device consisting of a suction-head 132 having openings at its under side for co-operation with the pieces in the magazine and being mounted on the 130

upper extremity of a carrier-lever 134 pivoted on the outer end of one of the previously mentioned levers 122, there being one of these heads for each canvas-feeding mechanism B. The same movement by the cam-groove 126 which has been already described as operating the platform-elevating ratchet mechanism lowers and raises the head 132, imparting to it a vertical component of the movement which causes it to enter the magazine, engage the top piece therein, and transfer it to an elevating leaf or support 136, by which the final delivery to the carrier-section 18 is made. The horizontal component of this transferring movement is derived from a cam-groove 138 in the opposite side of the disk 124 from the groove 126. A lever 140, fulcrumed about the same center as the levers 122, 122, has a roll operating in the groove 138 and is linked at 142 to one of the carrier-levers 134 for the suction-head and at 144 to a lever 146, which, at 148, is joined to the lever of the other suction-head. The canvas-retaining suction at the heads is created from the pump 30 through a pipe 150 including flexible sections, and is correctly timed to seize and release the pieces by a rotary valve 152 actuated by the shaft 38.

The leaves 136, already referred to as receiving the pieces of canvas from the transferring devices, are shown as normally lying in horizontal position adjacent to the carrier-section 18 when this is at the canvas-receiving position. Each leaf is pivoted upon brackets 154 rising from a supporting rod 156 extending transversely of the main frame (Figs. 4 and 13). A cleat 158 along its inner edge serves as a rest for the deposited piece, while the leaf is being elevated to a vertical position, presenting the canvas to the retaining action of the nozzles 26. This movement of the leaves is effected by a cam 160 upon the sleeve 44, it communicating movement to a lever 162, which, through a link 164, oscillates an arm 166 pivoted at 168. This arm is linked at 170 to one of the elevating leaves, and carries a gear-segment 172, which actuates the companion arm 166 and its leaf.

The leather-feeding mechanisms C are most completely illustrated in Figs. 1, 4, 6, 7 and 16. Each has a vertical magazine 180, in the form of a skeleton-frame, arranged for convenient removal from the main frame so the size of the pieces *c* operated upon and their container may readily be changed. These magazines are situated opposite the section 20 of the carrier when this is in its leather-receiving position. Against the outer edge of the bottom piece in each of the magazines moves a feeding slide 182 mounted to reciprocate in ways in a bracket 184 secured to the side of the frame F. The movement is effected from a cam-groove 186

(Figs. 16 and 18) in a disk 188 fast upon the sleeve 42. This groove receives a roll upon a lever 190 joined by a link 192 to a lever 194 arranged to rock about the sleeve 42. To the opposite extremities of the lever 194 and to levers 196, 196 are articulated links 198, 198, and the upper end of the levers 196 are linked at 200 to the respective slides 182. As each slide travels forward from the position illustrated in Fig. 16, it forces from the bottom of the corresponding stack, through an opening in the inner side of the magazine, a leather piece *c*, delivering this upon the horizontal surface of a cleated leaf 202. These leaves, which elevate the pieces *c* against the opposite faces of the carrier-section 20, may be in every respect the same as the leaves 136, which act upon the canvas pieces, and are shown as being operated in the same manner, their arms 204 being oscillated through a link 206, lever 208 and cam-groove 210 in the disk 188. In their vertical position, the leaves 202 force the pieces *c* against the spurs 34, which, as the leaves descend to their normal position, retain said pieces upon the section 20 for the operation upon them.

The pressure mechanisms D (Figs. 1, 4, 6, 8 and 11) cooperate first with the section 18 of the carrier A to produce the sewing ribs *a* upon the coated canvas pieces, and then with the section 20 to cause the adhesion of the formed canvas, which has been retained upon the pressure-surfaces of the mechanisms D, to leather pieces. Mounted to slide upon the rods 10, at each side of the guide member 12, is a cross-head 220, upon which is secured, to permit change of size, a plate 222 (Figs. 11 and 12) carrying a die 224, which has a groove 226 complementary to and arranged to register with the projection 22 of the die-section 18 of the carrier. Upon the rods 10, outside each cross-head, is an abutment-block 228, yieldable against springs 230 surrounding the rods and backed by nuts 232 threaded upon the outer portions of the rods. Variation in the position of these nuts permits a change in the normal relation of the operating surface of the die 224 to the opposed faces of the carrier-sections. Joining the cross-head and block is a toggle 234, connected by a link 236 to a lever 238 fulcrumed upon the rod 156. The opposite extremity of the lever 238 is similarly connected to the toggle of the associated cross-head. Depending from the lever 238 are arms 240 having rolls contacting with opposite portions of the peripheries of like cams 242, 242 secured to the sleeve 44. These cams provide for the movement of the dies 224, 224 into simultaneous co-operation with the sections 18 of the carrier and then with the sections 20, with the appropriate dwell to produce the rib-molding and assembling effects, and with intermediate pe-

riods of rest, during which the pressure-dies are separated from the carrier and other operations take place. To facilitate both the molding and assembling actions of the dies 224, each may be provided with heating means, indicated in Figs. 10 and 12 as consisting of electric units 244 set in the face of the head 220 behind the die-plate 222, the units receiving current through conductors 246. To free the sewing rib *a* from the groove 226, so the completed insole may be removed more readily from the die 224 by the carrier-section 20 after the canvas and leather pieces have been united, air-pressure 10 is introduced through passages 248 opening through the operating face of each die and extending through its mounting upon the cross-head. From these passages, pipes 250, including flexible sections, communicate with 20 the outgoing side of the pump 30. A rotary valve 252, included in the main run of the pipes 250 and actuated by the shaft 38, controls the work-ejecting air-blast.

Upon movement of the section 20 to the leather-receiving position, it carries upon its opposite faces two completed insoles, which must be removed before there are applied to it the pieces *c* which are to be included in the succeeding pair of insoles. Referring to 30 Figs. 1, 4, 5 and 9, there is pivoted upon the main frame, by means of a transversely extending shaft 258, an arm 260 of the delivering mechanism E. At its free end, this arm carries a plunger 262 urged downwardly, when the work-engaging position is considered, by a spring 264. The extent of this movement may be limited by a collar 266 threaded upon the upper end of the plunger and contacting with the arm, as is shown in the dotted-line position of the mechanism in Fig. 4. A reduced stem 268 upon the plunger is so situated that it may be swung in the movement of the arm into a cut-away portion 270 at the upper edge of the carrier-section 20. From the opposite sides of the stem 268 project lugs 272, upon which are pivoted jaws 274, with their grasping portions opposite the end of the stem. Links 276 join the jaws to the end of the lever 260, and cause the spring 264 to force said jaws away from the end of the stem 268. They may, however, be held temporarily in grasping relation to the stem by a latch 278 pivoted upon the arm and forced by a spring 280 toward the plunger, so it may be engaged by the inner side of the collar 266. The latch may be disengaged from the collar, to allow the jaws to retreat from the stem, by a toggle-connection 282 between the latch and the pivot-shaft 258 of the arm. When the collar and latch are in engagement, the toggle is straight. This is shown in full lines in Fig. 4. To break the toggle, as appears in dotted lines in Fig. 4, and thereby withdraw the latch from the collar,

said toggle is brought into contact with a relatively fixed member, here shown as adjustable, and furnished by a screw 284 threaded through a frame-projection. To oscillate the arm 260 between its opposite extremes, the shaft 258 has fast upon it a pinion 286, with which meshes a rack-bar 288 guided for vertical movement in the frame F. A link 290 (Fig. 9) unites the bar to a bell-crank lever 292, this having a roll entering a groove in a cam 294 secured to the sleeve 42 (Fig. 18). The action of the delivering mechanism is as follows: When the section 20 of the carrier arrives at the leather-piece-receiving position, bringing 70 upon its opposite faces completed insoles, the arm 260 is lowered until the stem 268 enters the depression 270 in the carrier-section and contacts with the edge of said section. This raises the plunger 262, and, through the connection of the jaws to the arm by the links 276, compels said jaws to close upon the opposite portions of the insoles, which rise slightly above the carrier, as is best shown in Fig. 5. When the work is thus 80 engaged, the collar 266 upon the plunger has been raised to a point allowing the latch 278 to be forced beneath it by its spring 280. With the two insoles thus grasped, the arm 260 is swung outwardly, drawing said insoles clear of the carrier, the upward incline of the spurs 34 facilitating the removal. When the mechanism E arrives outside the frame, the toggle 282 strikes the contact member 284, withdrawing the latch 278 from the collar. The spring 264 thereupon forces the stem 268 of the plunger away from the arm, thus separating the jaws by the action of the links 276 and releasing the soles, which may be deposited in a receptacle. 90

Now outlining the general operation of the machine, it will be assumed that the carrier A is at the right, as viewed in Fig. 1 of the drawings, this positioning the rib-forming section 18 in co-operation with the canvas-feeding mechanisms B, B, while the section 20 is aligned with the pressure mechanisms D, D. A cycle will be traced, beginning with the delivery to the carrier of the canvas pieces *b*. The actions at this time 100 occurring in connection with the section 20 and performed upon a preceding sole will be disregarded. With the carrier in the relation just indicated, the leaves 136, each of which already bears a piece *b* of canvas, are 110 raised by the elevating mechanism into a vertical position, bringing the pieces against the die-projections 22. Under the control of the valve 39, the pump 30 is now drawing air through the nozzles 26, so the pieces *b* 120 are held against the sections 18 while the leaves 136 resume their original horizontal positions. With the received pieces *b*, the carrier travels to the left (Fig. 1), while the suction-heads 132, in which the vacuum 130

is controlled by the valve 152, prepare for the delivery to the leaves of other pieces of canvas. The carrier having completed its movement, with the section 18 in registration with the pressure mechanisms D, D, the cross-heads 220 are moved toward the carrier, so that the die-recesses 226, in co-operation with the projections 22, form sewing ribs *a* in the canvas pieces, heat generated by the electric units 244 assisting in rendering these ribs more rigid. The nozzles 26 expand laterally under the pressure between the dies. The delivery of the canvas pieces to the leaves 136 continues, while the leaves 202 at the leather-feeding mechanisms C, C elevate previously supplied pieces *c* against the opposite surfaces of the carrier-section 20, where they are impaled upon and retained by the spurs 34. The cross-heads of the pressure mechanisms have retreated, carrying with them the formed pieces of canvas retained by the engagement of their ribs with the die-recesses 226. The carrier starts back to the right, the suction-heads returning from their delivery to the leaves 136, and the feed-slides 182 forcing from the magazines leather pieces *c* upon the now open leaves 202. Attaining its right-hand position, the carrier again presents its section 18 to the canvas-feeding mechanisms B, B, and its assembling section 20 to the pressure mechanisms D, D. The cross-heads of the latter, carrying the molded canvas pieces, are advanced to force latex-coated surfaces of said pieces against the leather pieces *c* held upon the spurs 34. The pressure between the opposed die members, aided by the heat applied by the electric units, produces a firm adhesion of the two pieces, completing the formation of the pair of insoles. When the cross-heads are withdrawn, the insoles are prevented from being carried with them and are compelled to remain on the carrier-section 20 by the blast of air delivered through the die-passages 248 and governed by the valve 252. During the assembling operations at section 20, a supply of the canvas pieces is occurring at section 18, as already described. At the leather-feeding mechanisms C, C, the leaves 202 are horizontal, and the slides 182 have advanced and delivered the pieces to them. The carrier is shifted to the left, and the delivery mechanism E descends, and, by contact of its stem 268 with the edge of the cut-away portion of the carrier-section 20, closes its jaws upon the upwardly projecting edges of the two insoles, and then draws these from the spurs, carrying them outside the frame. Here, contact with the member 284 opens the jaws, and the completed insoles are released. After the removal of the work, the leaves 202, with the leather pieces *c* upon them, are elevated to apply these pieces to the sections 20. The slides 182 have resumed their nor-

mal positions ready for the succeeding feeding operation. Canvas pieces *b* are being supplied to the leaves 136 ready for the next movement of the carrier to the right.

Having described our invention, what we claim as new and desire to secure by Letters Patent of the United States is:

1. In an insole-making machine, a carrier having a plurality of work-supporting sections movable to different operating positions, and a plurality of operating mechanisms at said positions, one of which mechanisms is arranged to coact with plural carrier-sections, while other mechanisms are arranged to coact with particular sections only. 75

2. In an insole-making machine, a carrier having a plurality of work-supporting sections movable to different operating positions, and a plurality of operating mechanisms at said positions and including a forming mechanism, said forming mechanism being arranged to coact with plural carrier-sections, while other mechanisms are arranged to coact with particular sections only. 85

3. In an insole-making machine, a carrier having a plurality of work-supporting sections movable to different operating positions, and a plurality of operating mechanisms at said positions and including a forming mechanism and feeding mechanisms, said forming mechanism being arranged to coact with plural carrier-sections, while the feeding mechanisms are arranged to coact, respectively, with other sections. 90

4. In an insole-making machine, a reciprocatory carrier having a plurality of work-supporting sections movable to different operating positions, and a plurality of operating mechanisms at said positions, one of which mechanisms is arranged to coact with all the carrier-sections, while the other mechanisms are each arranged to coact with one section only. 105

5. In an insole-making machine, a carrier having a plurality of work-supporting sections movable to different operating positions, and a plurality of operating mechanisms situated in pairs at said positions at opposite sides of the carrier, one of which mechanisms is arranged to coact with plural carrier-sections, while other pairs of mechanisms are arranged to coact with particular sections only. 115

6. In an insole-making machine, a reciprocatory carrier having a plurality of work-supporting sections, and work-delivering and pressure mechanisms with which the carrier co-operates in its reciprocation. 120

7. In an insole-making machine, a reciprocatory carrier having a plurality of work-supporting sections, feeding means arranged to deliver successively to the carrier, and pressure mechanism arranged to operate during each feeding operation. 125

8. In an insole-making machine, a reciprocatory carrier having a plurality of work-supporting sections, and work-delivering and pressure mechanisms arranged in pairs at opposite sides of the carrier and with which said carrier co-operates in its reciprocation.
9. In an insole-making machine, a carrier having two work-supporting sections and being movable to three operating positions, and operating means arranged to act upon the work.
10. In an insole-making machine, a carrier having two work-supporting sections movable to three operating positions, and operating mechanism arranged in duplicate at each of the three positions to act upon work at opposite sides of the carrier.
11. In an insole-making machine, a carrier having two work-supporting sections each of which is movable to two of three operating positions, and operating mechanism at each of the three positions arranged to act upon the work.
12. In an insole-making machine, operating mechanisms situated at three successive operating positions, a carrier having two work-supporting sections, and means for moving the carrier to present each section to an outer position and to the intermediate position to coact with the operating mechanisms thereat.
13. In an insole-making machine, operating mechanisms situated at three successive operating positions, a carrier having two work-supporting sections, and means for moving the carrier to present each section to an outer position and to the intermediate position to coact with the operating mechanisms thereat and simultaneously to present the companion section, respectively, to coact with the operating mechanisms at the intermediate and at the second outer position.
14. In an insole-making machine, a carrier having two work-supporting sections movable to three operating positions, operating mechanisms at the outer two of the three positions arranged to supply work-pieces to respective carrier-sections, and an operating mechanism at the intermediate position arranged to apply pressure to the delivered work-pieces.
15. In an insole-making machine, a carrier having an operating surface lying generally in a substantially vertical plane, work-feeding mechanism delivering to the operating surface, means for holding the pieces fed adjacent to the operating surface, and forming means co-operating with the carrier.
16. In an insole-making machine, a reciprocatory carrier having an operating surface lying generally in a substantially vertical plane, work-feeding mechanism delivering to the operating surface, means for holding the pieces fed adjacent to the operating sur-
- face, forming means, and means for moving the carrier for co-operation with the feeding and forming means.
17. In an insole-making machine, a carrier having an operating surface lying generally in a substantially vertical plane, work-feeding mechanism delivering to the operating surface, means mounted upon the carrier and arranged to engage the pieces fed near their upper edges, and forming means co-operating with the engaged pieces upon the carrier.
18. In an insole-making machine, a movable carrier having a forming section and an assembling section, and pressure mechanism with which the carrier-sections successively co-operate.
19. In an insole-making machine, a movable carrier having a forming section and an assembling section, pressure mechanism with which the carrier-sections successively co-operate, and feeding mechanism co-operating with the carrier.
20. In an insole-making machine, a movable carrier having a forming section and an assembling section, pressure mechanism with which the carrier-sections successively co-operate, and feeding mechanisms to which the carrier-sections are alternately presented, while the associated section co-operates with the pressure mechanism.
21. In an insole-making machine, a movable carrier having a forming section and an assembling section, pressure mechanism with which the carrier-sections successively co-operate, feeding mechanisms to which the carrier-sections are alternately presented, while the associated section co-operates with the pressure mechanism, and insole-delivering mechanism associated with one of the feeding mechanisms.
22. In an insole-making machine, a reciprocatory carrier having a rib-forming section and an assembling section, and a fabric-feeding mechanism, a pressure mechanism and an insole-body-feeding mechanism arranged for co-operation with the carrier.
23. In an insole-making machine, a movable carrier having a forming section and an assembling section, and opposite pressure mechanisms between which the carrier moves.
24. In an insole-making machine, a reciprocatory carrier having a rib-forming section and an assembling section, and fabric-feeding mechanisms, pressure mechanisms and insole-body-feeding mechanisms arranged successively in pairs at opposite sides of the carrier.
25. In an insole-making machine, a reciprocatory carrier having a rib-forming section and an assembling section, fabric-feeding mechanisms, pressure mechanisms and insole-body-feeding mechanisms arranged successively in pairs at opposite sides of the carrier, and delivering means associated

- with the insole-body-feeding mechanisms and arranged to grasp simultaneously two insoles upon the carrier.
26. In an insole-making machine, a die traveling between operating positions, and a die located at one of the positions and movable into and out of co-operation with the traveling die, such die identified with the particular position being provided with means for retaining an insole-piece upon it during the travel of the associated die.
27. In an insole-making machine, a die traveling between operating positions, a die located at one of the positions and movable into and out of co-operation with the traveling die, such die identified with the particular position being provided with means for retaining an insole-piece upon it during the travel of the associated die, and means for freeing the work from the retaining means.
28. In an insole-making machine, a die traveling between operating positions and having a rib-forming projection, a complementary grooved die located at one of the positions, and means for moving the grooved die toward and from the path of the traveling die to form an insole-piece between them.
29. In an insole-making machine, a die traveling between operating positions and having a rib-forming projection, a complementary grooved die located at one of the positions, and provided with a passage, means for delivering air under pressure to the passage, and means for moving the grooved die toward and from the path of the traveling die to form an insole-piece between them.
30. In an insole-making machine, a reciprocatory plate having a section provided with a rib-forming projection and a plane section, and means for reciprocating the plate through a plurality of operating positions.
31. In an insole-making machine, a reciprocatory plate having a section provided with a rib-forming projection and a plane section, plural feeding mechanisms and an intermediate pressure mechanism, and means for reciprocating the plate to alternately present its sections to the pressure mechanism and the other section to a feeding mechanism.
32. In an insole-making machine, a reciprocatory plate having a section provided with a rib-forming projection and a plane section, pressure mechanism provided with a grooved die complementary to the section of the plate having the projection, feeding mechanisms situated at opposite sides of the pressure mechanism, and means for reciprocating the plate to bring the sections alternately into co-operation with the pressure mechanism and with one of the feeding mechanisms.
33. In an insole-making machine, a re-
- ciprocatory plate having a section provided with a rib-forming projection and a plane section, pressure mechanism provided with a grooved die complementary to the section of the plate having the projection, fabric-feeding mechanism at one side of the pressure mechanism, insole-body-feeding mechanism at the opposite side of the pressure mechanism, and means for reciprocating the plate to bring the sections alternately into co-operation with the pressure mechanism and with one of the feeding mechanisms.
34. In an insole-making machine, a reciprocatory plate having a section provided with a rib-forming projection extending between opposite faces and with a section having opposite plane faces, and pressure mechanism co-operating simultaneously with the opposite sides of the same section and alternately with opposite sides of the two sections.
35. In an insole-making machine, a reciprocatory plate having a section provided with a rib-forming projection extending between opposite faces and with a section having opposite plane faces, pressure mechanism co-operating simultaneously with the opposite sides of the same section and alternately with opposite sides of the two sections, and feeding means arranged to deliver simultaneously to the opposite sides of a section.
36. In an insole-making machine, a reciprocatory plate having a section provided with a rib-forming projection and a plane section, pressure mechanism provided at each side of the plate with a grooved die complementary to the section having the projection, fabric-feeding means arranged to deliver simultaneously to opposite sides of the rib-forming section, and insole-body-material-feeding means arranged to deliver simultaneously to opposite sides of the plane-faced section.
37. In an insole-making machine, a reciprocatory plate having a section provided with a rib-forming projection and a plane section, work-retaining devices associated with each section, and means for reciprocating the plate through a plurality of operating positions.
38. In an insole-making machine, a reciprocatory plate having a section provided with a rib-forming projection and with suction devices and a plane section having retaining spurs, and means for reciprocating the plate through a plurality of operating positions.
39. In an insole-making machine, a reciprocatory plate having a section provided with a rib-forming projection and a plane section, plural feeding mechanisms and an intermediate pressure mechanism, insole-delivering mechanism associated with one of the feeding mechanisms, and means for reciprocating the plate to alternately present

its sections to the pressure mechanism and the other section to a feeding mechanism.

40. In an insole-making machine, a reciprocatory plate having a section provided with a rib-forming projection and a plane section, pressure mechanism provided with a grooved die complementary to the section of the plate having a projection, fabric-feeding mechanism at one side of the pressure mechanism, insole-body-feeding mechanism at the opposite side of the pressure mechanism, means for reciprocating the plate to bring the sections alternately into co-operation with the pressure mechanism 15 and with one of the feeding mechanisms, and mechanism associated with the body-material-feeding mechanism and arranged to grasp the work upon the plane section and remove it from the plate.

20 41. In an insole-making machine, pressure mechanism, a support having a substantially vertical operating face coacting with the pressure mechanism, and means arranged to receive insole-pieces in a substantially horizontal position and elevate and apply them to the operating face of the support.

42. In an insole-making machine, pressure mechanism, a movable carrier having a substantially vertical operating face coacting with the pressure mechanism, means arranged to receive insole-pieces in a substantially horizontal position and elevate and apply them to the operating face of the carrier, a magazine for insole-pieces, and means for transferring pieces from the magazine to the elevating means.

43. In an insole-making machine, pressure

mechanism, a movable carrier having a substantially vertical operating face coacting with the pressure mechanism, a work-piece-delivering member pivoted adjacent to the carrier, and means for elevating the member from a normally horizontal position into co-operation with the operating face.

44. In an insole-making machine, pressure mechanism, a movable carrier having a substantially vertical operating face coacting with the pressure mechanism, a retaining device associated with the operating face, and means arranged to receive insole-pieces in a substantially horizontal position and elevate and force them against the retaining device.

45. In an insole-making machine, plural pressure mechanisms, a reciprocatory plate having at its opposite sides substantially vertical operating faces coacting with the pressure mechanisms, and means arranged to elevate work-pieces simultaneously and apply them to the operating faces.

46. In an insole-making machine, plural pressure mechanisms, a reciprocatory plate having at its opposite sides substantially vertical operating faces coacting with the pressure mechanisms, means arranged to elevate work-pieces simultaneously and apply them to the operating faces, a magazine situated at each side of the path of the plate, and transferring mechanism movable between each magazine and the elevating means.

In testimony whereof we have signed our names to this specification.

ERNEST E. SABIN.
ERIC A. HOLMGREN.

CERTIFICATE OF CORRECTION.

Patent No. 1,667,951.

Granted May 1, 1928, to

ERNEST E. SABIN ET AL.

It is hereby certified that error appears in the printed specification of the above numbered patent requiring correction as follows: Page 9, line 64, claim 46, strike out the word "by"; and that the said Letters Patent should be read with this correction therein that the same may conform to the record of the case in the Patent Office.

Signed and sealed this 30th day of April, A. D. 1929.

(Seal)

M. J. Moore,
Acting Commissioner of Patents.
